UNITED STATES PATENT OFFICE.

GILBERT A. WATERHOUSE, OF QUINCY, MASSACHUSETTS.

HAND SCREW-CLAMP.

SPECIFICATION forming part of Letters Patent No. 410,303, dated September 3, 1889.

Application filed May 1, 1889. Serial No. 309,243. (No model.)

To all whom it may concern:

Be it known that I, GILBERT A. WATERHOUSE, of Quincy, in the county of Norfolk, State of Massachusetts, have invented a certain new and useful Improvement in Hand Screw-Clamps, of which the following is a description sufficiently full, clear, and exact to enable any person skilled in the art or science to which said invention appertains to make and use the same, reference being had to the accompanying drawings, forming part of this specification, in which—

Figure 1 is a perspective view showing my improved clamp in use; Fig. 2, an enlarged top plan view of the clamp with the screws removed; Fig. 3, a horizontal longitudinal section of the adjustable jaw, and Fig. 4 a sectional view showing details of construction.

Like letters of reference indicate corresponding parts in the different figures of the drawings.

My invention relates to hand screw-clamps which are provided with an adjustable jaw; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the fixed jaw; B, the movable jaw; C, the fulcrum-screw, and D the clamping-screw. The fixed jaw and screws are of the ordinary form and construction and arranged in the usual manner. The jaw B is divided longitudinally into two sections b d, hinged together at f to open or separate horizontally. The section b is provided on its inner face with a longitudinal tongue g, adapted to enter a corresponding groove in the section d to prevent vertical movement of said sections. The jaw B is provided with openings h i for the screws, surrounded by a metallic collar or guide-ring k, provided with slotted arms l, in which screws m in the upper face of the jaw-sections work and prevent said sections from becoming separated or opened too far. A laterally-arranged chamber p, Fig. 3, is formed in the jaw-sections near the screw-opening i, and a coiled spring

q is disposed therein, said spring acting expansively to throw said sections open. A horizontally-arranged rod r, Fig. 3, is secured by a nut t in the section b and projects laterally through an opening v in the section d. A curved cam or clamping lever x is pivoted at y to the free end of the rod r, the point of said cam engaging a wear-plate z on the outer face of the jaw.

In the use of my improvement, when it is desired to adjust the clamp to an object, as H, instead of turning the screws C D until the movable jaw engages said object, the lever x is thrown back into the position shown by dotted lines in Fig. 2. This frees the section d and permits the spring q to act to throw said sections apart, thus disengaging the threaded opening i from the screw D and permitting the jaw B to slide readily on the screws until stopped by the article to be clamped. The lever x is then moved inward, forcing the jaw-sections together, so that its threaded opening i will take on the screw D, which may then be operated in the usual manner to complete the clamping process. The collars k serve to guide the jaw on the screws when its sections are separated, and its slotted arms l, working on the pins m, guide said sections as they are forced together again by the lever x, as described.

Having thus explained my invention, what I claim is—

1. In a clamp of the character described, a fixed jaw, fulcrum-screw, and clamping-screw, in combination with a movable jaw provided with screw-openings and divided longitudinally into two sections hinged together at one end, a clamping-lever for fastening said sections together, and a spring for separating them when released, substantially as described.

2. In a clamp of the character described, a fixed jaw, fulcrum-screw, and clamping-screw, in combination with a movable jaw having screw-openings and divided longitudinally into two sections hinged together at one end, a rod secured in one section and projecting through an opening in the opposite section, a cam-lever pivoted to the free end of said rod, and a spring for separating said sections, substantially as described.

3. In a clamp of the character described,

the combination of a fixed jaw, fulcrum and clamping screws, a movable jaw having screw-openings and divided longitudinally into sections tongued and grooved on their inner faces 5 and hinged together at one end, a coiled spring disposed in a chamber in said jaw and acting expansively to force its sections apart, a rod secured in one section and projecting through an opening in the opposite section, a 10 cam-lever pivoted to said rod, and guide-collars for said screws provided with slotted arms working on pins in the movable jaw-sections, substantially as described.

4. In a hand screw-clamp, the jaw A and 15 screws C D, in combination with the jaw B, comprising the hinged sections b d, the collars k, having the slotted arms l, working on

pins m, and mechanism, substantially as described, for locking said sections together.

5. In a hand screw-clamp, the jaw A and 20 screws C D, in combination with the jaw B, comprising the hinged sections b d, tongued and grooved at g and provided with screw-openings h i, chamber p, and opening v, the spring q in said chamber, the rod r, projecting through the opening v, the cam-lever x, pivoted to said rod, and the collars k, having the slotted arms l working on pins m, substantially as described. 25
